(57) **CLAIM**

The ornamental design for a cup and saucer set as shown and described.

DESCRIPTION

FIG. 1 is a front, right and top perspective view of a cup and saucer set, showing my new design.

FIG. 2 is a rear, left and bottom perspective view of the cup and saucer set of FIG. 1.

FIG. 3 is a front, right and top perspective view of a cup of the cup and saucer set in FIG. 1.

FIG. 4 is a rear, left and bottom perspective view of the cup of FIG. 3.

FIG. 5 is a front elevation view of FIG. 3.

FIG. 6 is a rear elevation view of FIG. 3.

FIG. 7 is a left side elevation view of FIG. 3.

FIG. 8 is a right side elevation view of FIG. 3.

FIG. 9 is a top plan view of FIG. 3.

FIG. 10 is a bottom plan view of FIG. 3.

FIG. 11 is an enlarged view of detail 11 in FIG. 3.

FIG. 12 is an enlarged view of detail 12 in FIG. 4.

FIG. 13 is a front, right and top perspective view of a saucer of the cup and saucer set in FIG. 1.

FIG. 14 is a rear, left and bottom perspective view of the saucer of FIG. 13.

FIG. 15 is a front elevation view of FIG. 13.

FIG. 16 is a rear elevation view of FIG. 13.

FIG. 17 is a left side elevation view of FIG. 13.

FIG. 18 is a right side elevation view of FIG. 13.

FIG. 19 is a top plan view of FIG. 13.

FIG. 20 is a bottom plan view of FIG. 13; and,

FIG. 21 is an enlarged view of detail 21 in FIG. 13.

The dot-dash broken lines in FIGS. 3-4, 11-13, and 21 depict the boundaries of the enlarged views and form no part of the claimed design.

1 Claim, 21 Drawing Sheets
